UNITED STATES PATENT OFFICE.

FRIEDRICH KARL BEYER, OF BIELEFELD, AND CONRAD WERNER WILHELM THEODOR LIST, OF HANOVER, GERMANY.

SPITTOON.

SPECIFICATION forming part of Letters Patent No. 743,226, dated November 3, 1903.

Application filed December 2, 1902. Serial No. 133,611. (No model.)

To all whom it may concern:

Be it known that we, FRIEDRICH KARL BEYER, residing at 3 Güsenstrasse, Bielefeld, and CONRAD WERNER WILHELM THEODOR LIST, residing at 13 Rambergstrasse, Hanover, in the Kingdom of Prussia and Empire of Germany, subjects of the King of Prussia, Emperor of Germany, have invented certain new and useful Improvements in Spittoons, of which the following is a full, clear, and exact description.

This invention has reference to spittoons which may be carried in the pocket of the user.

15 Drawings illustrating our invention are annexed hereto, in which—

Figure 1 is a vertical section of the spittoon, taken at the line A B, Fig. 4. Fig. 2 is a side elevation. Fig. 3 represents a vertical section taken at the line C D, Fig. 4. Fig. 4 is a plan view showing the spittoon in the open position. Figs. 5 to 9 are details. Fig. 10 is a sectional view on a line corresponding to the line E F of Fig. 1.

25 Referring now to the drawings, *a* represents the casing of the spittoon, which consists of a cup-shaped part to which the lid *b* is hinged. A projection *c* is provided at the front of the lid *b*, behind which the projection *d* of the 30 spring *f*, which is disposed around the bottle *e*, engages when the spittoon is in its closed position, Fig. 1.

In the front of the casing *a* a hole *g* is provided, preferably of rectangular form, through 35 which protrudes the button *h* of the spring *f*, and in order that the button *h* may not be accidentally pressed, and thereby cause the spittoon to open when in the pocket, a pad *i* is disposed around the upper part of the aperture *g* on the casing *a*.

40 The object of the casing *a* is to protect the receptacle *e* from breakage and also to prevent the sputum being visible to the user; but when it is desired at any time to examine the condition of the sputum—say by a medical attendant—the glass *e* may be removed from the casing *a*. The receptacle *e* and casing *a* have preferably no sharp corners, so that the principal hygienic requirement of easy cleaning may be fulfilled.

45 The vessel *e*, together with its closing ap-

pliance, fits in the casing so as to be easily removed and replaced again in position, and, for example, consists of glass, and on its front, lower, and back sides has a longitudinal 55 groove *k*, into which the spring *f* fits.

The neck *l* of the vessel is preferably of oval or funnel shape, as shown, so as to obtain as large a “spitting-opening” as possible.

60 The receptacle *e* is preferably transparent in order to facilitate inspection by, say, a medical attendant.

At the back of the spring *f* are connected cheeks *m*, having holes *n*, to which is respectively hinged one free end *o* of the clip or clasp *q*, which surrounds the closing-stopper *p*.

65 The front part of the clip *q*, which is preferably made of wire, is turned up into a projection *r*, so that when the pocket-spittoon is opened the projection *c* of the casing-cover *b* seizes the wire clip *q*, together with the stopper *p*, and carries with it both these parts, so opening the receptacle for use.

70 The water-tight closing of the receptacle *e* is attained by the pressure upon the stopper *p*, which is of an elastic nature, and when the pressure of the casing *b* upon the rubber stopper *p* ceases, as by actuating the button *h* of the 75 spring *f*, the elasticity of the stopper *p* will cause the cover *b* to be raised, and by turning back of this cover *b*, which, as previously stated, carries with it the stopper *p*, the receptacle *e* is opened.

80 The spring *f* may be secured in position or released by simply pushing it on or off the vessel *e*.

85 The button *h*, which protrudes through the front of the casing *a*—i. e., through the hole *g*—holds the vessel *e*, with its entire closing means, firmly in the casing *a*, so that by simply pressing the spring *f* against the receptacle *e* the casing and receptacle, with the closing appliances, are easily and quickly detachable from each other.

90 What we claim, and desire to secure by Letters Patent, is—

95 In the device of the character described, a casing approximately cup-shaped having a 100 cover hinged on its upper portion, said cover being provided with a projection at the front,

a receptacle adapted to fit in the casing,
said receptacle having a longitudinal groove
formed on its upper outer surface, a spring
adapted to fit in said groove, a stopper adapt-
ed to fit in the throat of the receptacle, and
means for securing the stopper in the recep-
tacle.

In witness whereof we subscribe our signa-
tures in presence of two witnesses.

FRIEDRICH KARL BEYER.

CONRAD WERNER WILHELM THEODOR LIST.
